(57) **CLAIM**

The ornamental design for a controller for forceps for medical robot, as shown and described.

DESCRIPTION

FIG. 1 is a front, top and left side perspective view of a controller for forceps for medical robot, showing our new design;

FIG. 2 is a front, top and right side perspective view thereof; FIG. 3 is a front elevational view thereof; the opposite side being a mirror image thereof;

FIG. 4 is a top plan view thereof;

FIG. 5 is a bottom plan view thereof;

FIG. 6 is a left side elevational view thereof; and,

FIG. 7 is a right side elevational view thereof.
